UNITED STATES PATENT OFFICE.

OTTO J. KUENHOLD, OF CLEVELAND, OHIO.

GAS-FURNACE.

1,161,776.

Specification of Letters Patent.

Patented Nov. 23, 1915.

Application filed September 6, 1910, Serial No. 580,530. Renewed October 18, 1915. Serial No. 56,612.

To all whom it may concern:

Be it known that I, OTTO J. KUENHOLD, citizen of the United States, residing at Cleveland, in the county of Cuyahoga and State of Ohio, have invented certain new and useful Improvements in Gas-Furnaces, of which the following is a specification.

My invention relates to a gas furnace, and in which arrangement both economical production and distribution of the heat units is effected. This of course involves the most complete combustion along with the most practical application of the heat possible to the exposed surfaces, a desideration always 15 in heating systems but seldom fully attained.

Specifically I claim for my invention,—

First,—thorough mixture of the air and gases to promote complete combustion.

Second, the proper proportion of air, particularly providing against a large surplus air supply as this would be very injurious for the following reasons:—It dilutes the mixture thereby preventing complete combustion; it cools the flame below the ignition point of some of the constituent gases; it cools the inner surfaces of the boiler or furnace; it absorbs heat and carries it up the chimney.

Third,—affords an equal distribution of the circulation so that all the heat absorbing and transmitting surfaces do a fair share of work.

Fourth,—the bringing of the temperature of the flame up to as high a point as possible so that every particle of the mixture is raised to or beyond its ignition point.

Fifth,—providing a liberal combustion chamber above the burners so that combustion is entirely completed before the products come in contact with any cooling surfaces, such as water tubes, and other heat absorbing parts.

Sixth,—a thorough insulation so that the heat generated does not escape except as it is absorbed into the water or air to be heated within the furnace.

Seventh,—making all parts simple, substantial, and easily removable or accessible for repairs.

In the accompanying drawings, Figure 1 is a longitudinal sectional elevation of the furnace showing the general air and smoke circulation as applied to a certain hot water boiler which is the subject matter of an application for Letters Patent concurrent here-

with in the Patent Office and bearing Ser. No. 580,999, filed September 6, 1910. Fig. 2 is a transverse section on line *a*—*a*, Fig. 1, showing the individual burner compartments and the combustion chamber. Fig. 3 is a horizontal section or plan on line *b*—*b*, Fig. 1, and showing the burner compartments in three several conditions as hereinafter fully described. Fig. 4 is a perspective view of one of the burners. Fig. 5 is a detail of the burner and grate lifter. Fig. 6, Sheet 2, shows an enlarged longitudinal section through one of the burner compartments with a complete equipment of grate and other parts for different kinds of fuel. Fig. 7 is a horizontal section on the line *c*—*c* of Fig. 6, through the mixer of one of the burner compartments and particularly shows the controlling devices for the air and gas supply to burners. Fig. 8 is a section on line *d*—*d*, of Fig. 6.

The furnace as thus shown is adapted especially for a hot water heating system for residences and the like, but it may also be utilized for the generation of steam, and is provided with an air intake chamber *A*, an ashpit or bottom portion beneath the hard fuel grate which is sub-divided into three several chambers *B*, *B'* and *B''* front to rear into which the air passes from chamber *A* for the combustion of whatever kind of fuel is used.

The circulation of the air and gases is shown by the arrows Fig. 1. The air is taken in through the screened opening 1 at the rear of the furnace into the air intake chamber *A* and passes through this into the series of burner compartments *B*, *B'*, *B''* through openings 2 in the intervening wall and which may be opened or closed or regulated by means of doors or dampers 3. Each of these said burner compartments contains a burner 6 complete with a mixer 7 which curves upward and the burner opens at its top into a combustion chamber *C* common to all said burner compartments or chambers. Each burner compartment is a complete unit, having individual air and gas control entirely independent of the others and adapted to be separately used. There may be any number of these burner compartments, say one or more, according to the size of the furnace. Over each compartment or chamber there is a grate or grate section 5. A sufficient space remains at the edges of said

burners to afford upward draft from beneath, the products passing thence upward into and through the so-called heater compartment D.

5 The heater compartment D is utilized for heating the water, and while this part of the furnace does not come within this application I may say that I employ a number of hollow water circulating units or castings 10 (not shown) and arranged side by side and adapted to be connected together at I and O respectively similar to a cast iron radiator, the exterior surfaces of each unit being of such shape that when so assembled a series 15 of horizontally inclined smoke flues 66 are left between the said units, and also vertical smoke passages 50 and 64 at the front and rear respectively and with which the flues 66 communicate. Suitable walls 46, 47 and 20 48 meet and close the heater chamber D, at the top, back and bottom, and a removable cover 36 closes the front. The outermost units form the sides, so that the entire heater chamber D is inclosed except for smoke inlets 50 at the front and outlets 64 at the back 25 and openings 49 at the lower rear for purposes later set forth.

The structure thus described may be varied, the essential point being that there is a 30 chamber D over the chambers A and C through which the products of combustion pass and wherein heating is accomplished.

After the fuel is completely consumed or burned up the products pass from combustion chamber C upward through passages 35 50, flues 66 and outlet passages 64 into the transverse hood 41 and out at E to the chimney by means of pipe 40. The damper 38 above in conjunction with doors 3 below 40 gives perfect control of the draft and air supply. The outlet pipe 40 fits within instead of without a thimble 67 cast on the hood 41. This is to cause the drippings or condensation to run into the structure instead of over the outside as is generally the 45 case with them. An annular flange 39 on the inside of the smoke outlet passage E acts as a stop for the smoke pipe. The drippings from the smoke pipe 40 as well as any other drippings drop through openings 49 between the water heating units above described but not shown into the pan P from which they are drained by means of pipe 43. Door 42 gives access to the pan. This pan 50 is of metal and completely covers and separates chamber A from the parts above or over the same. A partition 33 separates chambers A and C and considerable heat radiates through this partition and through 55 the pan P into the air intake chamber A, thus preheating the air supply to the several burner compartments B, B', B''. There is also considerable downward radiation within the burner compartments from the fire, 60 and this, in addition to the preheating of

the air in the intake chamber A provides a highly heated air supply to the mixers through air intakes 66 and to the flames as well. This is a distinct advantage, as it promotes a high temperature of combustion. 70

The relatively large combustion chamber over the burner compartments insures the protection of flames against being chilled below ignition point by coming in contact with water tubes, or similar heat absorbing surfaces. 75

From the preceding it is seen that every possible precaution is taken to insure that every particle of the gas and air mixture attains its ignition point and is burned before escaping. 80

To promote a thorough intermixture or admixture of air and gases, a perforated plate or woven wire screen 68 is placed in the burner as shown in Fig. 6, and the gases 85 must pass through this screen to the exit jets or holes. The further use of this plate is to prevent "backfiring" of the burner or the ignition of the gas jet which shoots the raw gas into the mixer. It is necessary to take some 90 such steps to prevent such backfiring with a construction in which heated air is fed to the mixer and in which the burner becomes very hot (sometimes red hot in my case). I rely principally upon careful proportioning of 95 the mixer, burner and other associated parts to avoid the "backfiring" but prefer to add this screen as an additional preventive. It also gives a more equal flame over the burner because it equally distributes the gas beneath 100 the same to all parts of the burner.

I may observe that in general the obtaining of a thorough intermixture of the air and gas is a matter of proper proportion and careful design rather than of any new 105 invention over the existing state of the art.

By placing each burner in or over a separate burner compartment and having an independent air inlet door 3 for each compartment I am enabled to control the exact 110 amount of air received by each burner and to shut off the air to those compartments not being used. This enables me to fulfil the important and generally neglected requirement that there shall not be a large surplus 115 of air supplied. This surplus air cools the interior surfaces of the boiler or furnace and absorbs heat and carries it up the chimney, and has other disadvantages as hereinbefore noted. 120

The frame or wall around chambers A, B, C and the lower portion of the furnace is made up of side plates 63 held together by end plates 30 and 44, floor plate 32, center division wall 33 and pan P. Upon this wall 125 is placed the heater D, the whole being bolted or riveted together. The combustion chamber has heat resisting linings 35, 62 and 34. Door 29 gives access to the combustion chamber, grates, and burners. The 130

individual burner compartments B, B' and B'' are formed by inserting partitions or division plates 27 between them and which are preferably made of a hard, compressed mixture of asbestos and Portland cement. This does not warp, corrode or expand appreciably under the heat.

The construction of the burners and mixers is best shown in vertical longitudinal section in Fig. 6, in transverse section Fig. 2 and in plan by Fig. 3. A perspective view of the burner is shown by Fig. 4.

Referring particularly to Fig. 6 the burner consists substantially of a hollow elongated box shaped member or part having a number of perforated projections or jet nozzles in its top through which the gas escapes under more or less pressure. The said burner rests upon ledges 54 and 55 at its ends and can be removed by simply lifting it out after first having removed the grates 5. The said burners also have flanges 14 at their ends added to center the burners in their compartments so that they properly seat onto the mixing tubes and maintain a central position in the burner compartment. The gas inlet for the burner is at the bottom through mixing tube 7 and preferably near the center, and has concentric rings 51 and 52 about it between which a soft fire-proof washer or packing is placed. The mixer tube 7 is curved upward at its rear and has a flange 53 to fit between the above concentric rings of the burner which with the interposed packing makes a practically gas tight connection. By thus placing an annular recess in the burner instead of on the mixer, it casts easier and cannot become filled with ashes.

A rod 9 running transversely through the furnace passes through lugs 56 (see Fig. 6) on the inner end of the mixing tubes and supports the same in working position, screws 10 serving to fasten said parts together. The ends of said rod project through the first or lower outer wall or casting of the furnace. Lugs 13 and 14 on the top of the burner support the grate and prevent it from sagging under the intense heat. Perforated lugs 12 and 15 in the grate and burner respectively are for the purpose of lifting them out by means of the lifter Fig. 5. This lifter has a projection 70 which is adapted to enter holes in the lugs, when they can readily be lifted out even when red hot. The toe 71 and the heel 72 on the lifter prevent the burner or grate from rotating on the projection 70.

In case the gas supply gives out or if for any other reason it is desired to burn solid fuel alone, the grate and burner are lifted out and removed and then the grate is restored but seated down on the shelves 54 and 55 previously occupied by the burner. Then the furnace is ready to burn coal or

wood or other solid fuel. The lowering of the grate gives a correspondingly greater depth of firepot which is required for solid fuel. The removal of the burners also allows a more copious draft as required by solid fuel as well as preventing clogging up of the burner openings which would occur if they remained in place. When the grate is so placed a disk 11 cast into the same covers the mixer opening at the top so that no ashes can fall into it. A rotatable tube 8 set into the front wall of the furnace about the front end of mixer tube 7 is adapted to close the air inlet holes or openings 66.

Two equivalent and alternate ways of controlling the doors 3 are shown. In both of these a rod 4 is connected to lugs 26 on the door and passed through the front frame where the gate may be controlled. The first discloses an index plate 37 on the front frame, see Fig. 3. The outer end of said rod is bent at right angles to this plate 37 and the position of this bend indicates on the said index plate the position of the door 3 in relation to its opening.

The other or alternative way is shown in Figs. 6 and 7. In this latter case the said rod is connected to the gas valve 18 so that the handle of this actuates the air supply door as well as the gas supply. In the illustration given a plug gas valve 18 is used, the plug 60 having an elongation 61 on which a lever 19 is secured by means of nut 59 or otherwise. To this lever 19 the rod 4 is attached. The closed position is shown and both air and gas supply are shut off. By opening the gas valve 18 the lever 19 is caused to push on rod 4 which opens the gate 3. The friction of the said valve will hold the gate in any position. With this arrangement when burning solid fuel the air draft supply is controlled either through ash door 31 or by having a main gas valve at 69, Fig. 3, which can then be turned off and the air supply controlled by means of the gas valve lever 20, Fig. 7. It will be noted that the pivot point of the gate 3 is a little above the middle thereof, Fig. 1, so that it is in a sense a butterfly valve. This is the preferred construction as two streams of air then flow into the burner, the one below the gate being thrown well toward the front and the upper one supplying the rear end of the burner. The distribution of the air supply is therefore even, which is important. The gate 3 is made heaviest at the top so as to counterbalance in all positions.

The gas shoots into the mixer through nozzle 16, Fig. 6, which is a piece of pipe having a drilled screw plug 17 at its end and the other end is screwed into the valve casting. The rotatable sleeve 8 over the outer portion of the mixer tube 7 is so made that a quarter turn thereof closes the opening 66 through or in the side of mixer tube 7.

One end of this sleeve as well as of the mixing tube projects out through the casing or wall of the furnace, and the outer end of said sleeve has a flange 57 with a finger or index 21 to indicate the condition of the mixer openings 66 as to being open or closed. A projecting plug 58 facilitates rotating this sleeve, and a set screw 74, Fig. 8, may be used to fix the adjustments thereof although ordinarily the friction is sufficient. Lugs 22 and 23 limit the rotation of said sleeve 8. A washer 65 holds the sleeve in place, the valve 18 bearing against said washer.

The valves 18 are each connected to a pipe 24 running across the front of the furnace, Fig. 7, and which is supported by brackets 25 which are bolted to the front end of the furnace. By unbolting these brackets the pipe 24, valves 18 and nozzles 16 can all be pulled out from the furnace as one unit. The sleeve 8 can then be withdrawn and by first removing the rod 9 and lifting out the burners and grates, I can remove the mixing tubes 7 and partitions 27, which latter are guided in lugs, etc. on the frames 30 and 33.

A door 31 allows the removal of the ashes from all the burner compartments. Gas may be turned on while burning solid fuel so as to ignite same or assist in its combustion the leakage about the disk 11 being sufficient to afford a lighting flame, said disk being a rough casting which does not make a close or gas tight fit. In each side of the burners there is a hole 73, Fig. 4. When the burners are all in place, these holes are opposite those of adjacent burners, and, when the gas is turned on, a jet shoots out from these holes, there being a corresponding hole 74 in the partition 27 so that the jets of adjacent burners may meet. The purpose of this construction is that when one burner is lighted it will automatically light an adjacent burner when the gas has been turned on and so on across the series. This is done gradually and without puff if the proportions are right and the gas is turned on gradually.

A pilot light is purposely omitted from this system and the user is simply required to open the door 29 to ignite the burners, thus avoiding danger of explosion due to leakage of gas into the combustion chamber previous to igniting.

The door 29 extends entirely across the front of the furnace so that any explosion occurring due to leakage or escape as above mentioned is unconfined and can therefore do no great damage when lighting occurs. The chances are that any dangerous mixture

in the combustion chamber will immediately escape when the door is opened.

Solid fuel and gas are never burned together in this furnace and the parts 5 are grates for the solid fuel.

What I claim is:

1. In a furnace, a burner and a mixer therefor taking its air supply from within said furnace, and means to govern the flow of air into the mixer, means outside of said furnace to control the air supply within the furnace and an index indicating the amount of air opening of said mixer.

2. In a furnace, a series of burner compartments each having separately and externally controllable air inlets, in combination with a mixer in each compartment taking its air supply from within said burner compartment but controllable from without.

3. In a furnace, a series of burner compartments each containing an externally controllable mixer, an air supply chamber communicating with each of said burner compartments through externally and individually controlled openings, and means whereby the air is heated in the air supply chamber.

4. In a furnace, a series of burners and individual chambers therefor having partitions between them, said chambers having a small flame opening on each side of each burner, and said partitions provided with holes opposite the said flame openings, so that the said flames may meet and ignite adjacent burners.

5. In a furnace, a chamber having a burner and below it an externally controllable air inlet to the chamber and without the furnace a valve controlling the fuel supply to the burner and means for connecting the said air inlet control to the said fuel control valve so that the air inlet is opened with and at the same time as the fuel supply and the air inlet opening being in proportion to the fuel supply opening.

6. A furnace having a series of burner compartments provided with separate controllable air inlets at their rear and an air supply chamber located behind said inlets, in combination with means for preheating the air in said chamber by the outgoing products of combustion, and dampers to control said inlets.

In testimony whereof I affix my signature in the presence of two witnesses.

OTTO J. KUENHOLD.
